CONVERTIBLE DAVENPORT AND BED

Thomas F. Cooney, New Haven, Conn.

Application October 24, 1940, Serial No. 362,616

5 Claims. (Cl. 5—31)

This invention relates to an article of furniture, and more particularly to a combined davenport and bed so constructed that it may be readily extended for use as a full-size or half-size bed, as desired, and folded into a position to serve as a davenport.

In a piece of furniture of this character it is desirable to provide such a construction that the device, when extended as a bed, shall be at substantially the same height as when used as a davenport or settee. It is also desirable to provide such a construction that the extension of the device may be accomplished with a minimum of effort, and that the folding or reversion of the device into a davenport may be similarly accomplished. It is also desirable that the device may be only partly extended, so as to serve as a child's bed, and that it may be locked in any desired position of extension, within limits, so that the back may be substantially upright if desired, or may be in a reclining position. The above advantages, among others, all are contemplated in the article of furniture herein illustrated.

One object of the invention is to provide a combined davenport or settee and bed such that the device will, when folded, have the appearance of the ordinary davenport, and which may at the same time be readily and easily converted into a bed without the addition of further pads or mattresses.

A further object of the invention is the provision of a combined davenport and bed such that the surface upon which the user sits when the device is used as a davenport will be substantially at the same height as that of the surface upon which the person reclines when the device is used as a bed.

A still further object of the invention is the provision of a combined davenport and bed in which is provided a main structure or frame and an auxiliary or slidable structure, which may be slidably removed from the main structure when desired to form a bed, and which slidable structure may be locked or secured in any one of a number of extended positions, as well as to be locked in the completely stored position.

A still further object of the invention is the provision of a combined davenport and bed provided with sufficient cushion or mattress portions to form the upper surface of the bed, and which mattress portions may all be contained in the structure when used as a davenport, in such a compact position that room is provided for a drawer or the like to hold the necessary bedding, so that the device may be a complete entity in

itself, whether employed as a bed or as a davenport.

To these and other ends the invention consists in the novel features and combinations of parts to be hereinafter described and claimed.

In the accompanying drawings:

Fig. 1 is a front elevational view of an article of furniture embodying my invention, the article being shown in the position to be used as a davenport or settee;

Fig. 2 is a transverse sectional view on line 2—2 of Fig. 1;

Fig. 3 is a partial sectional view similar to Fig. 2 but showing the parts in a slightly different position;

Fig. 4 is a sectional view on line 4—4 of Fig. 2;

Fig. 5 is a partial sectional view showing the device in partly open position for use as a child's bed;

Fig. 6 is a view similar to Fig. 5 showing the device in full open position for use as a full-length bed; and

Fig. 7 is a detail front elevational view of one corner of the bed as extended.

To illustrate a preferred embodiment of my invention, I have shown in Fig. 1 of the drawings an article of furniture such as a davenport, for example, having side frames 10 and 11, which side frames are connected by rods 13 and 14, by the frame member 15, and by the rods 16 and 17 of the back frame 18. The forward portion of the two end frames is also connected by the member 19 extending between the two end frames, this member, however, terminating short of the end frames but connected thereto by U-shaped metal straps 20, as shown more especially in Fig. 4. The members 20 are provided with upwardly turned edge portions 21, for a purpose to be hereinafter described. These connecting members hold the end frames rigidly together and provide the main frame of the device, which is adapted to support the movable parts to be hereinafter described. These end frames are provided with feet 21 at each corner upon which the device rests solidly upon the floor.

Within the main frame of the device is supported a movable or outwardly slidable section which comprises front and rear members 23 and 24, which are connected by end sections. These end sections are hollow, as shown in Fig. 4, and consist of outer and inner members 25 and 26 spaced apart by upper and lower rails 26a. These end sections and the front and rear members 23 and 24 form a hollow rectangular frame to support other movable parts of the device, as will

presently be described. The end sections of this portion of the frame are slidably supported by the end sections 10 and 11 of the main frame of the device, and at the forward corners of the device the front member 23 may be provided with downwardly extending legs 28 carrying supporting rollers 29 designed to rest upon the floor. This slidable support comprises a groove 11^a in each of the end frames 10 and 11, and a roller 29^a rotatably mounted upon each of the end members 25 rotatable in and resting upon the lower edges of the grooves. It will be understood that this section of the device and the parts attached thereto may be drawn forwardly from the main frame previously described, as shown, for example, in Fig. 6, the rollers 29 rolling upon the floor and the front portion of the movable section being supported from the floor, while the rear portion of the movable section is supported by the rollers 29^a.

Pivoted at its ends to the upper portion of the front section 23 is a reversible pad or cushion 30, the pivot points being shown at 31 at substantially the central portion of this cushion with respect to the thickness thereof, so that, whether the cushion is swung to folded position, as shown in Fig. 1, or swung to an extended position, as shown in Figs. 5 and 6, the height of the upper surface thereof will be substantially the same. This cushion, as stated, is reversible so that either side may be used, and it will of course be obvious that when in the position of Fig. 1, one surface is used as a seat, while in the position of Figs. 5 and 6 the opposite surface is used as a portion of the mattress of the bed. This cushion or pad may, therefore, be provided with a substantially rigid hollow rectangular frame 32 disposed substantially centrally of the thickness of the cushion, so that the upholstering of the latter may extend above and below this frame.

To the front face of the cushion 30 are pivoted at 33, by means of laterally extending ears 34, a pair of legs 35, these legs being adapted to be moved downwardly to supporting position, as shown in Figs. 5, 6 and 7, in which position the movement of the legs is limited by the stop 36 against which the upper portion of the legs contacts, so that they may be folded to a position parallel with the cushion, as shown in dotted lines in Fig. 7. When in extended position they will serve to rest upon the floor and support the cushion 30 when it has been swung outwardly to convert the device into a bed, as in Figs. 5 and 6.

A second cushion or mattress section 38 is also carried within the movable or sliding auxiliary frame, previously described. This cushion is also provided with a substantially rigid frame having lower transverse members 39 adjacent each end of the device. These members 39 are provided with notches 40 adapted to receive and be supported by pins 41 provided upon toggle members 42, which members are pivoted at their lower ends to a link 43, which is in turn pivoted to the upper ends of toggle links 44, the latter being pivoted at 45 to the end frames of the auxiliary section. While the link 43 and the toggle levers 42 and 44 connected thereto are provided within the end frames, the pins 41 project from these frames through arcuate openings 46 to support the members 39, which are disposed between these end frames, although closely adjacent thereto at each end of the device. From the foregoing description it will be apparent that the cushion or mattress section 38 is arranged for vertical movement within the sliding auxiliary

frame according to whether the toggle links 42 and 44 are extended as shown in Fig. 6, or are contracted or folded as shown, for example, in Fig. 2. Fig. 3, as will be hereinafter explained, is an intermediate position of these members.

Pivoted to each of the end frames, as shown at 50, is a lever 51 to the lower end of which is pivoted one end of a link 52, the other end of which is pivotally connected to the member 43. The upper end of the lever 51 is provided with a pin 52^a extending through the end frame member of the auxiliary frame by virtue of a curved slot 53 in the latter, the pin 52^a lying within an elongated slot 54 in a link 55 pivoted at 56 to the frame member 32 of the cushion 30. It will be understood that the toggle mechanism heretofore described, as well as the members 51 and 55 and associated mechanism, is duplicated at each end of the device so that the cushion or mattress portion 38 will be raised or lowered evenly at both of its ends. From this construction it will be obvious that as the levers 51 are moved about their pivots 50, the link 43 will be moved to and fro, as shown in Fig. 3, thus serving to move the toggles 42 and 44 from the position shown in Fig. 2 to the position shown in Fig. 6, and vice versa, thus serving to raise and lower the mattress portion 38.

As shown more especially in Figs. 2 and 5, a back cushion portion 60 is provided. The lower forward corner of this member is hinged to the mattress section 38 by means of hinge straps 61 and 62 connected respectively to the cushion members, and pivoted together at 63 at the upper rear corner of the mattress portion 38 and the lower forward corner of the back cushion 60.

In order that the auxiliary sliding frame may be drawn to any desired extended position and locked in such position, a locking plate 65 is provided in each of the end portions of the auxiliary frame, these plates having teeth 66 on their lower edges to engage with the upwardly turned edges 27 of the straps 29. One end of each of the members 65 is pivotally supported from one of the end frames by the link 67, while the other is movably supported by means of a slot and pin connection 68. The member 65 may also be provided with a slot 69 to clear the pivot pin of the forward lever 44. To the member 65 is connected an operating bar 70 extending upwardly to a point adjacent the member 55, and provided, as shown in Fig. 4, with a laterally turned end 71 extending through the end section of the auxiliary frame to be engaged by this member. The operating bar 70 is also provided with a shoulder 72 against which acts a compression spring 73 normally acting to hold this member upwardly, in which position the teeth 66 would be out of engagement with the members 27. However, when the cushion 30 is in its folded position, that is, when the device is to be used as a davenport, as shown, for example, in full lines in Fig. 2, or when the member 38 is in extended position, as shown in full lines in Figs. 5 and 6, the members 55 (shown in dotted lines in these figures) engage the upper end 71 of the operating bars and move the members 65 into an extended position where they will engage the members 27 when in a position over these members.

In order to assist in the raising of the mattress portion 38, a spring 75 may be provided, as shown in Fig. 3, one end of this spring being secured at 76 to the frame, and the other end being secured to one of the toggle members 44, so that this spring is tensioned when the mattress portion 38

is in its lower position, and thus will serve to assist in the straightening of the toggles and the raising of the mattress section. It might sometimes occur that, when the mattress section is in raised position, and the toggles straightened out, as shown in Fig. 6, the parts would lock in this position and not begin their movement to folded position. To insure the initiation of this return movement, a spring 71 may be connected to the other toggle member 44 and to the member 76, this spring acting to return the toggles to folded position. The strength of this spring may be considerably less than that of the spring 75, so as not to interfere seriously with the action of the latter, but at the same time have enough strength to merely "break" the toggles when the pivots thereof are in their aligned positions, shown in Fig. 6, the spring 71 being tensioned and the spring 75 being substantially free from tension at this time.

It will be noted that when the device is in its folded position, as shown, for example, in Fig. 2, the mattress or cushion sections 30 and 38 are supported in closely adjacent positions one immediately below the other, the portion 30 resting upon the portion 38 to be supported thereby, in addition to the support afforded by the pivot 31. As these two mattress portions are at the upper portion of the movable frame, sufficient space is provided in the lower portion thereof for a drawer 80 extending across the front of the movable frame portion, as shown in Fig. 1, and if desired, the entire depth of this frame, as shown in Fig. 5. This drawer may contain linen, blankets and other bedding to be used when the device is converted into a bed. The drawer may be supported at the inner portion of the end members of the auxiliary frame in any desired way.

The operation of the device will now be described. As shown in Fig. 1, and in full lines in Fig. 2, the parts are in position for use as a settee or davenport, the back cushion 60 resting against the frame 13, and it will be noted that the operating bar 79 is depressed and the teeth 66 of the member 65 in engagement with the upwardly turned edge 27 of the strap 20, so that the device is locked in closed position. If it is desired to extend the device, the cushion or mattress portion 30 is swung upwardly about the pivot 31 from the position shown in full lines in Fig. 2 to the position shown in full lines in Fig. 5. During the initial part of this movement, that is, between the full-line and the dotted-line position of the member 30, as shown in Fig. 2, the link members 55 disengage the upper ends of the operating bar 70 and release the teeth 66 from the members 27, and as the members 55 move outwardly, the slots 54 travel over the pins 52^a until, when the member 30 reaches the dotted-line position shown in Fig. 2, the pins 52^a are at the rear end of these slots. Further pivotal movement of the member 30 thus moves the lever 51, as shown, for example, in Fig. 3, and by means of movement of this lever the toggle links 42 and 44 are straightened out or moved from the position shown in Fig. 2 through that position shown in Fig. 3 to their final position shown in dotted lines in Fig. 6, which will be reached when the member 30 is in its horizontal extended position, shown in Fig. 5. It will be apparent that as the pivot 31 is centrally located with respect to the thickness of the member 30, the upper side of this member will be at the same vertical height as was the upper side (also the reverse side when in the position of Fig. 2). In

the meantime, the mattress portion 38 has been moved upwardly by the toggle links to the position shown in Fig. 5, so that its upper side is at the same level as that of the member 30. As the member 39 has been moved upwardly, so also has the back cushion 60, due to the pivotal connection between these two members at 63; the back member 60 merely sliding upwardly along the rear frame 18. In this position the device will be used as a child's bed or as a "chaise longue." As the member 30 is in horizontal position, the link 55 will again engage the upper end of the bar 70, so that the teeth 66 will lock against the member 27.

The auxiliary frame may now be moved outwardly with respect to the main frame of the device to any extent desired. If it is merely desired to move it outwardly a short distance, so that the back portion 60 assumes an attitude of less inclination, this may be done. The member 30 must first be raised slightly so as to raise the member 55 from engagement with the ends of the member 70, and thus release the teeth 66. When it has been moved outwardly to the desired extent, the member 30 is released so that it will be supported from the floor by means of the legs 35, and the locking teeth 66 are again forced downwardly into an engagement with the members 27.

If desired, the auxiliary frame may be drawn outwardly to its full extended position, as shown in Fig. 6, wherein the device is adapted to be used as a full-length bed. In this position the back cushion 60 is drawn forwardly and drops downwardly until its rear end rests upon and is supported by the rod 14 in a horizontal position and in correct alignment with the mattress portions 38 and 30. It will be noted in this position that as shown the bar 65 has moved beyond the straps 29, as it will not be necessary to lock the device against further outward movement.

In restoring the device to its original position, it is only necessary to fold the back cushion 60 about its hinge 63 upon the mattress portion 38, and push inwardly upon the cushion 30 to move the sliding frame inwardly from the position shown in Fig. 6 to that shown in Fig. 5. The back cushion 60 can then be swung upwardly against the back frame 18, and the cushion portion 30 swung upwardly and inwardly about its pivot 30, thus lowering the mattress portion 38 to its original position and reconverting the device into the davenport shown in Fig. 1.

While I have shown and described a preferred embodiment of my invention, it will be understood that it is not to be limited to all of the details shown, but is capable of modification and variation within the spirit of the invention and within the scope of the appended claims.

What I claim is:

1. A davenport bed construction comprising a main frame having rigidly connected end sections, an auxiliary frame slidably connected to said main frame for retraction between said sections or extension therefrom, a unitary cushion member pivoted to said auxiliary frame to swing upwardly and outwardly, a second cushion member mounted for substantially vertical movement in said auxiliary frame, means carried by the latter frame for supporting said second cushion, said means comprising members supporting said cushion from below, means for raising and lowering said members in unison, said last-named means comprising two pairs of toggle members adjacent each end of the cushion, a link connecting one pair thereof with the other pair, a

lever pivoted to the frame and having one end connected to said link, and a second link having a lost-motion connection with said lever and connected to the first cushion.

2. A davenport bed construction comprising a main frame having rigidly connected end sections, an auxiliary frame slidably connected to said main frame for retraction between said sections or extension therefrom, a unitary cushion member pivoted to said auxiliary frame to swing upwardly and outwardly, a second cushion member mounted for substantially vertical movement in said auxiliary frame, means carried by the latter frame for supporting said second cushion, means connecting said first cushion to said supporting means for moving the latter upwardly when said first cushion is swung pivotally, and locking means to lock said auxiliary frame in extended position, said locking means being controlled by the movement of said first-named cushion.

3. A davenport bed construction comprising a main frame having rigidly connected end sections, an auxiliary frame slidably connected to said main frame for retraction between said sections or extension therefrom, a unitary cushion member pivoted to said auxiliary frame to swing upwardly and outwardly, a second cushion member mounted for substantially vertical movement in said auxiliary frame, means carried by the latter frame for supporting said second cushion, means connecting said first cushion to said supporting means for moving the latter upwardly when said first cushion is swung pivotally, and locking means to lock said auxiliary frame in extended position, said locking means being controlled by the connection between said first cushion and the supporting means.

4. A davenport bed construction comprising a main frame having rigidly connected end sec- 40

tions; an auxiliary frame slidably connected to said main frame for retraction between said sections or extension therefrom, a unitary cushion member pivoted to said auxiliary frame to swing upwardly and outwardly, a second cushion member mounted for substantially vertical movement in said auxiliary frame, means carried by the latter frame for supporting said second cushion, means connecting said first cushion to said supporting means for moving the latter upwardly when said first cushion is swung pivotally, and locking means to lock said auxiliary frame in extended position, said locking means being spring pressed toward inoperative position and said connecting means moving said locking means to operative position when said first-named cushion is in a horizontal position.

5. A davenport bed construction comprising a main frame having rigidly connected end sections, an auxiliary frame slidably connected to said main frame for retraction between said sections or extension therefrom, a unitary cushion member pivoted to said auxiliary frame to swing upwardly and outwardly, a second cushion member mounted for substantially vertical movement in said auxiliary frame, means carried by the latter frame for supporting said second cushion, means connecting said first cushion to said supporting means for moving the latter upwardly when said first cushion is swung pivotally, and locking means to lock said auxiliary frame in extended position, said locking means being spring pressed toward inoperative position and said connecting means moving said locking means to operative position when said first-named cushion is in a horizontal position either when disposed between the end frames or when swung outwardly to an extended position.

THOMAS F. COONEY.
